E. P. STEVENS.

BAFFLE MEANS FOR FIRE BOXES.
APPLICATION FILED FEB. 20, 1914.

1,172,318.

Patented Feb. 22, 1916.

UNITED STATES PATENT OFFICE.

ENOCH P. STEVENS, OF CHICAGO, ILLINOIS, ASSIGNEE, BY MFSNE ASSIGNMENTS, TO
AMERICAN ARCH COMPANY, OF NEW YORK, N. Y., A CORPORATION OF DELAWARE.

BAFFLE MEANS FOR FIRE-BOXES.

1,172,318.

Specification of Letters Patent. Patented Feb. 22, 1916.

Application filed February 20, 1914. Serial No. 819,888.

To all whom it may concern:

Be it known that I, ENOCH P. STEVENS, a citizen of the United States, residing at Chicago, in the county of Cook and State of Illinois, have invented certain new and useful Improvements in Baffle Means for Fire-Boxes, of which the following is a specification.

My invention relates to baffle means for fire-boxes, and refers particularly to baffle means to be used within the fire-boxes of coal-burning locomotives.

In many classes of locomotives fire-brick arches are used for the purpose of deflecting the products of combustion in order to provide a longer path through which such products must pass before entering the boiler flues. In many cases it is usual to support such arches on water-cooled arch tubes which extend upwardly and rearwardly of the fire-box from the flue sheet thereof.

In many locomotives it is difficult, if not impossible, to employ supporting arch tubes, on account of the dimensions of the fire-box. It is to locomotives of this character that my invention is directed.

My baffle means consist of one or more baffle walls supported at their ends against the side sheets and being arranged in a substantially vertical plane, so that the gases of combustion are deflected before entering the boiler flues. I prefer to employ two of such baffle walls, the front one of which is located higher than the rear one, but I do not confine myself to any particular number of such baffle walls, as one or a greater number than two could readily be employed.

It is a further object of my invention to employ such a construction that each of the baffle walls may be constructed of a plurality of bricks or tiles which are securely locked together in order to retain their position in the fire-box.

A still further object of my invention consists in providing the baffle walls with passages and apertures through which air, steam, or other gases, may be discharged in order to promote combustion and to consume smoke. Such gases are introduced into the baffle walls through the supporting means located on the side sheets of the fire-box.

These and other advantages of my invention will be more readily understood by

reference to the accompanying drawings, in which:

Figure 1 is a fragmentary vertical longitudinal section through a locomotive fire-box taken on the line 1--1 of Fig. 2. Fig. 2 is a vertical transverse section taken through the fire-box shown in Fig. 1, this section being taken parallel with the front and rear surfaces of the baffle walls. Fig. 3 is a fragmentary horizontal section taken on the line 3--3 of Fig. 2. Fig. 4 is a fragmentary horizontal section through the locomotive fire-box, on a reduced scale, showing a plan of the baffle walls.

The fire-box 10 is provided with the flue sheet 11, from which the flues 12 extend in a forward direction. On its top the fire-box 10 has the crown sheet 13, and on its sides the side sheets 14. Exterior to each of the side sheets 14 is an external side sheet 15, thereby forming the side water legs 16 between the sheets 14 and 15. In the lower portion of the fire-box 10 are located the grate bars which, for the sake of simplicity, have not been shown in the present drawings.

The baffle means which I employ consists in the baffle walls 17 and 18, which are of identical construction, so that a description of one baffle wall will serve as a description of the other. The front baffle wall 18 is preferably located on a higher plane than that of the rear baffle wall 17.

Located on the side sheets 14 are the supporting members 19, each of which consists of a hollow casting, having the outlet 20 and the inlet 21, 22 and 23. Each of these inlets extends into a ring 24, which passes from the external side sheet 15 to the inside side sheet 14. A steam injector pipe 25 is placed opposite the inlet 22, so that steam mixed with air may be forced into the hollow casting 19. Each of the inlet members 23 is provided with a shoulder 26, the object of which will appear hereafter.

Each of the baffle walls 17 and 18, as clearly appears from Figs. 1 and 2, is upwardly arched, and at the same time is forwardly arched, so that the rear face of each baffle wall is concave. In this way each baffle wall forms a pocket-like structure, and allows a better admixture of the gases of combustion with the air and steam in-

duced into the fire-box, as will be described hereafter. Each of the baffle walls consists of the two lower bricks 28 and 29, which interlock with a tongue and groove joint, as indicated in Fig. 3. At their outer ends these bricks are shaped to be supported on the shoulders 26 of the inlet members 23 of the supporting castings 19. The outer ends of the bricks are also recessed in order to fit around the supporting castings 19. On their upper edges the bricks 28 and 29 are provided with the recesses 30 and 31. The upper bricks 32 and 33 of each of the baffle walls 17 and 18 are supported on the upper edges of the lower bricks 28 and 29 respectively, and have projections 34 which extend over the inlet members 21 of the supporting castings 19. On the lower edge of each of the bricks 32 and 33 are the recesses 35 and 36, which register with the recesses 30 and 31 of the lower bricks 28 and 29. Keys 37 are placed between the recesses 30 and 35 of the lower bricks 28 and 29 and the upper bricks 32 and 33 in order to lock the upper bricks to the lower bricks. The passages 38, formed by the recesses 31 and 36, are allowed to remain open and register with the outlets 20 of the supporting castings 19. As clearly shown in Fig. 2, the recesses 30 and 31 and 35 and 36 do not extend to the inner ends of the bricks 28, 29, 32 and 33.

The apertures 39, 40 and 41 extend from the passages 38 to the rear faces of the baffle walls, these apertures being larger the nearer they are to the side sheets.

Having thus described the various parts used in connection with my invention, its operation may now be readily understood. After the baffle walls 17 and 18 have been placed in position, in normal operation of a locomotive, steam is admitted through the injector pipes 25. This steam draws air along with it, not only through the inlet openings 22, but also through the inlet openings 21 and 23. If the amount of air thus entrained with the steam is too great in proportion to the steam, the openings 21 and 23 may be plugged up. The mixed steam and air pass through the outlet openings 20 into the passages 38 and are then expelled through the apertures 39, 40 and 41 into the locomotive fire-box, thereby assisting the process of combustion by reason of the added oxygen and serving to consume smoke. The steam also serves to prevent the formation of slag in the apertures 39, 40 and 41. In order to obtain an even distribution of the steam and air expelled through the apertures 39 to 41 inclusive, I have found it necessary to make the apertures nearest to the center line of the baffle wall smaller than the apertures near the outer ends of said wall.

The gases rising from the bed of fuel are,

for the most part, first deflected upwardly by the baffle wall 17, and then passing over the upper edge of the same, the larger part of said gases pass between the baffle walls 17 and 18 and then below the baffle wall 18 to the boiler flues 12. Smaller portions of the gases of combustion pass below the baffle wall 17 directly to the flues 12 and also above the baffle wall 18 to said flues. By reason of this lengthening the path through which the greater part of the gases of combustion pass, I have found that greatly superior results are attained, while at the same time the addition of steam and air to these gases still further promotes perfect combustion.

It will be apparent to those skilled in the art that many changes could be made in the detailed construction of the parts which I have described without departing from the spirit and scope of my invention.

What I claim is:

1. Baffle means for fire-boxes, comprising the combination with the side sheets of the fire-box, of supporting means on said side sheets, and a substantially vertical upwardly and forwardly inclined baffle wall extending between said supporting means, substantially as described.

2. Baffle means for fire-boxes, comprising the combination with the side sheets of the fire-box, of supporting means on said side sheets, a baffle wall extending between said supporting means and consisting of upper and lower bricks and means for locking said bricks together, said baffle wall having a passage therethrough and between said bricks, said passage having a plurality of apertures communicating with said flues, and means for introducing gas into said passage, whereby said gas will pass through said apertures into said fire-box, substantially as described.

3. Baffle means for fire-boxes, comprising the combination with the side sheets of the fire-box, of supporting means on said side sheets, a baffle wall extending between said supporting means, said baffle wall consisting of a pair of lower bricks engaging each other at their inner edges, a pair of upper bricks resting on the upper edges of said lower bricks and locking means between said upper and lower bricks, a passage through said baffle wall, said passage having a plurality of apertures communicating with the interior of said fire-box, and means for introducing gas into said passage, whereby said gas will pass through said apertures into said fire-box substantially as described.

4. Baffle means for fire-boxes, comprising the combination with the side sheets of the fire-box, of hollow supporting means on said side sheets, a baffle wall extending between said supporting means and consisting of a pair of upper and lower bricks engaging each other at their inner edges, a passage through

upper bricks resting on the upper edges of said lower bricks and locking means between said upper and lower bricks, passages extending inwardly from said supporting means between said upper and lower bricks, said passages provided with apertures communicating with the interior of said fire-box, and means for introducing gas from said supporting means into said passages, whereby said gas will pass through said apertures into said fire-box, substantially as described.

5. Baffle means for fire-boxes, comprising the combination with the side sheets of the fire-box, of hollow supporting means on said side sheets, each of said supporting means provided with a gas outlet, an upwardly and forwardly arched baffle wall extending between said supporting means,

said baffle wall consisting of a pair of lower 20 bricks engaging each other at their inner edges, a pair of upper bricks resting on the upper edges of said lower bricks and locking means between said upper and lower bricks, passages extending inwardly through 25 said wall from the outlets of said supporting means and between said upper and lower bricks, said passages being provided with a plurality of apertures extending through the rear surface of said wall, and means for 30 introducing gas into said hollow supporting means, whereby said gas will pass through said passages and said apertures into said fire-box, substantially as described.

ENOCH P. STEVENS.
